(57) **CLAIM**

The ornamental design for a cylindrical camera charging base, as shown and described.

DESCRIPTION

FIG. 1 is a top, front, left side perspective view of a cylindrical camera charging base, shown in condition of use; FIG. 2 is a top, front, left side perspective, showing my new design;

FIG. 3 is a bottom, front, right side perspective view thereof; FIG. 4 is a front elevational view thereof; Monday, Jan. 30, 2017

FIG. 5 is a rear elevational view thereof;

FIG. 6 is a right side elevational view thereof;

FIG. 7 is a left side elevational view thereof;

FIG. 8 is a top plan view thereof; and,

FIG. 9 is bottom plan view thereof.

In the drawings, the broken lines depict environmental subject matter and form no part of the claimed design.

1 Claim, 5 Drawing Sheets
